UNITED STATES PATENT OFFICE.

IPHUS H. GORDON AND CLARENCE E. MILES, OF LYNDONVILLE, VERMONT.

LATCH FOR VEHICLE DOORS.

Application filed December 19, 1921. Serial No. 523,386.

To all whom it may concern:

Be it known that we, IPHUS H. GORDON and CLARENCE E. MILES, citizens of the United States, residing at Lyndonville, in 5 the county of Caledonia and State of Vermont, have invented certain new and useful Improvements in Latches for Vehicle Doors, of which the following is a specification.

This invention relates to door latches and 10 is intended more particularly for application to automobile and other vehicle doors, but it is, of course, capable of use upon any swinging closure. The object of the invention is to provide a latch which will effectively retain the door in closed position 15 without rattling and which will be set to hold the door in closed position without slamming or otherwise applying great force to the door. The invention seeks to provide 20 a latch having the stated characteristics which will be simple in construction and arrangement and capable of production at a low cost, while possessing a high degree of efficiency in actual use.

25 The invention is illustrated in the accompanying drawings, in which—

Figure 1 is a view showing our improved latch in top plan;

Fig. 2 is a view similar to Fig. 1 but showing the latch casing in horizontal section and also showing the parts in the position assumed immediately prior to the door reaching the fully closed position;

Fig. 3 is an elevation of the latch showing the same in retracted position;

Fig. 4 is a similar view but looking at the opposite side of the latch.

The vehicle body 1 and the door 2 may 40 be of the usual or any preferred design, the door being mounted to swing in a horizontal plane in the usual manner. The door is constructed with a chamber 3 adjacent its free edge in which the latch is mounted, and in the edge of the vehicle body at the door 45 opening is a transverse groove 4 leading from the outer side of the body to a keeper or strike 5, the said keeper or strike consisting preferably of a metallic plate set into the edge of the body at the door opening and secured by any convenient means 50 and provided with a slot or opening 6 disposed vertically and having its vertical walls converging away from the door opening, as clearly shown in Fig. 2.

55 The latch is mounted upon and between an outer plate 7 and an inner plate 8 which

are connected by bolts or screws 9 in the usual manner and are adapted to be secured in the chamber 3 of the door by any convenient fastenings. The outer plate 7 60 will preferably seat within a channel or groove 10, as shown in Figs. 1 and 2, while the inner plate 8 extends to the free edge of the door and is there provided with a lateral flange 11 which extends across the 65 outer open end of the chamber 3 and is formed with a slot or opening 12 through which the latch member 13 may project to engage the slot 6 in the keeper. The latch 13 is preferably a cam or eccentric having its 70 working edge 14 tapered, as shown clearly in Fig. 2, whereby it may fit snugly within the slot 6 of the keeper and thereby effectively retain the door in closed position, while at the same time preventing all rattling of the door. The latch cam or eccentric 13 is carried by a spindle 15 which is 75 rotatably mounted in the inner latch plate 8 and in the body of the door and is equipped at its inner end with a lever or 80 crank handle 16. The outer end of the spindle may be extended through the door and equipped with an outer handle or knob 17, but this handle or knob 17 is not indispensable, especially when the latch is applied to 85 open vehicles. A spring 18 is coiled around the spindle 15 between the latch and the inner surface of the door body, and has one end secured to the spindle and the other end secured to the door. The spring tends 90 constantly to throw the latch to working position and, consequently, holds the handle 16 yieldably in the position assumed by it when the door is fully closed, but light pressure applied manually to said handle will 95 serve to overcome the force of the spring and withdraw the latch from the keeper so that the door may be opened. We also provide a spring 19 which is preferably in the form of a resilient plate disposed at 100 the rear of the latch and bearing upon the edge of the same above the spindle, as shown clearly in Figs. 3 and 4, the inner or lower end of the plate being coiled, as shown at 20, whereby it may be held upon one of the bolts or screws which secure the latch plates 7 and 8 together. This coiled formation also increases the force exerted by the spring upon the cam or eccentric to move the same to its working position. The latch cam or eccentric is also provided in its outer 105 face with a notch or recess 21 and arranged 110

to bear against the said face is a leaf spring 22 provided with a lug or projection 23 adapted to engage the notch 21, the end of the spring projecting beyond the edge of the latch and playing in the groove 4 so that it may impinge against the edge of the keeper 5, as shown at 24, whereby when the door is closed, the latch will be automatically released. It will be readily noted that the retaining spring 22 has one end secured at the back of the chamber 3 containing the latch and is shaped to converge toward the latch from its secured or anchored end and the lug or tooth 23, consequently, bears constantly against the outer face of the latch so that it will instantly engage the notch 21 when the latch has been rocked so as to bring said notch into alignment with the lug. The closed position of the parts is shown in Fig. 1. If it be desired to open the door, the spindle 15 is rotated against the tension of the spring 18 by force exerted upon the handle 16 or the handle 17 and the latch is thereby rocked so that its tapered edge 14 will be withdrawn from the keeper and the outwardly swinging movement of the door will cause the latch to clear the keeper, as will be readily understood upon reference to Fig. 2. When the latch has been thus rocked, the lug or tooth 23 on the retaining spring or dog 22 will instantly engage the notch 21 and the latch will then be restrained against reverse movement, the spring 18, however, being under an increased tension. When the door is again closed, the latch will, of course, clear the edge of the door opening in the vehicle body, but the free end of the dog 22 will enter and move along the groove 4 and impinge against the edge of the keeper, whereupon the continued swinging closing movement of the door will effect disengagement of the lug 23 and the recess 21, whereupon the latch will be moved into engagement with the keeper by the action of the springs 18 and 19, as will be readily understood. The beveled form of the slot 6 in the keeper and the working edge of the latch permits these parts to effect a very close engagement so that the door will be very effectually held in closed position and all tendency of the same to rattle will be overcome. Moreover, as the parts wear through long-continued use, the latch will accommodate itself to the greater movement permitted by the wearing away of the op-

posed surfaces so that it will enter into deeper engagement with the keeper when the door is closed.

It will be readily noted that our latch is exceedingly simple in the construction and arrangement of its parts and may be applied readily to any swinging closure at a very low cost. When the door is fully closed, the cam is so nearly on a dead center that it will resist all efforts to open the door and must be manually rolled back to permit opening of the door. In the closed position of the door, the spring back of the cam holds the door firmly on its hinges, thus preventing rattling of the hinges, and, as the latch is above the center of the door, the cam is constantly pulling up on the door so that, in actual service, the latch holds the door firmly in all directions.

Having thus described the invention, what is claimed as new is:

The combination with a body having a door opening, and a swinging closure adapted to fit within said door opening, one edge of the door opening being provided with a transverse groove, of a keeper secured in the edge of the door opening and extending across the inner end of said groove and provided with a slot having its side walls converging away from the door opening, an eccentric mounted in the closure for rocking movement in a plane intersecting the plane of movement of the closure, said eccentric having a tapered edge adapted to fit within the slot in the keeper and being provided in one side face with a notch, a spindle rotatably mounted in the closure and carrying said eccentric, a retaining spring secured at one end in the closure and disposed adjacent the side of the eccentric and provided with a lug adapted to engage the notch therein, the free end of said spring being adapted to play in the groove in the body and impinge against the edge of the keeper, a spring coiled around the spindle and having one end secured to the closure and its opposite end connected with the spindle and eccentric, and a pressure spring secured in the door at the rear of the eccentric and bearing upon the eccentric above the spindle.

In testimony whereof we affix our signatures.

IPHUS H. GORDON. [L. S.]
CLARENCE E. MILES. [L. S.]
